UNITED STATES PATENT OFFICE

ARTHUR GEOFFREY RENDALL, OF BIRMINGHAM, ENGLAND, ASSIGNOR TO MORLAND & IMPEY LIMITED, OF BIRMINGHAM, ENGLAND

CARDS FOR USE IN STATISTIC MACHINES

Application filed April 29, 1926, Serial No. 105,618, and in Great Britain May 8, 1925.

In the recording or analysis of statistical matter perforated cards are commonly used, the cards being passed through machines of various kinds. Ordinarily a stack of superimposed cards is placed in a machine and the cards are removed individually from the stack by a slide mechanism acting on the bottom card. Difficulty is often experienced with the cards used for these and like purposes, due to damaging of the edges of the cards, particularly the forward edges. Slight defects in the said edges will often result in crumpling of the cards, and consequent stoppage of the machine, during the transition of the cards from the stack to another position.

The object of the present invention is to enable the cards ordinarily used to withstand more effectively the action of the machines, and for this purpose the invention comprises the impregnation of the cards at one or more edges, or borders, or over the whole of either or both surfaces, with varnish or like material. In particular the invention comprises the treatment of the strip from which the cards are cut, in the manner hereinafter described.

Figure 1 of the accompanying drawings shows a card treated in accordance with this invention.

Figure 2 shows a coiled strip from which the cards are usually cut.

In carrying the invention into effect I prefer to use a varnish consisting of a solution of synthetic resin such, for example, as a phenol formaldehyde condensation product. The varnish may be applied to the cards, or the strip from which the cards are cut, by a roller, pad or spray, or in any other convenient manner. In the example shown in Figure 1, the varnish is applied to both longitudinal edges and borders of the card *a* to an extent indicated by *b*. The varnish soaks into the card and becomes practically invisible. It also interferes in no way with the subsequent printing of the card as the ink can be deposited over the varnished portion as well as on the plain portion of the card. If desired the varnishing may be effected immediately prior to printing, the cards being caused

to traverse a drying region before entering the printing machine, so that the varnishing and subsequent printing are effected as parts of one operation.

Although the term varnish is used in the claims accompanying this specification it is to be understood that such claims include the equivalents of varnish for the purpose of the present invention.

If desired the cards may be treated over the whole of one or both sides. Further the treatment may be effected by means of any suitable varnish or impregnating fluid. Varnishes of different colours may be used as a means for distinguishing between cards of different kinds.

By so treating the cards the edges are rendered more rigid and much better able to withstand the deteriorating action of the machines, and the delay and inconvenience caused by failure of the cards is thereby minimized. The hardening effect caused by the varnish may be further increased by passing the treated card between hot rollers.

Preferably the application of the varnish is applied in the following manner. The strips from which the cards are cut are usually made up in the form of a relatively large coil as shown in Figure 2, the convolutions lying in tight or close contact. While the strip is so coiled, varnish is applied by means of a pad, brush or spray to one or both of the flat sides of the coil, and the varnish is allowed to soak through and between the edges of the strip, the depth to which the varnish penetrates depending on the amount applied. After drying the strip is uncoiled and cut into lengths in the usual manner.

While it is preferred to impregnate the cards throughout their area, the portions of the cards which really need such impregnation are the edges thereof, because it is there that the damage occurs in their use in statistical or accounting and tabulating machines.

It will be understood therefore that while in the claims specific reference is made to impregnation of the cards at their edges, such impregnation may extend inwardly throughout the body of a card.

Having thus described my invention what I claim as new and desire to secure by Letters Patent is:—

1. The process of hardening cards for use in statistic machines including the steps of impregnating the card at and inside its edges with an ink retaining varnish and then drying said varnish.

5 2. A card for use in statistic machines impregnated at and inside its edges with a hardening, ink-retaining varnish.

10 In testimony whereof I have signed my name to this specification.

ARTHUR GEOFFREY RENDALL.
